UNITED STATES PATENT OFFICE.

ALVAH A. GRINER, OF CHICAGO, ILLINOIS.

STAIR STRUCTURE.

973,109.

Specification of Letters Patent. Patented Oct. 18, 1910.

Application filed December 2, 1909. Serial No. 530,946.

To all whom it may concern:

Be it known that I, ALVAH A. GRINER, a citizen of the United States, residing at Chicago, in the county of Cook and State of Illinois, have invented certain new and useful Improvements in Stair Structures, of which the following is a specification.

My invention relates to an improvement in the construction of sheet metal stairs of that type in which the treads of the stairs are covered with a plastic material, such as concrete.

The principal object of my invention comprehends the production of a device of the above character which is adjustable, and of such construction that the risers and treads may be riveted together individually, and the sections formed thereby kept in stock in large quantities, ready to be carried to the job and assembled in place on the stair stringers, the adjustment permitting the height of the risers and the length of the treads to be adjusted according to the specification of the stairs, as the sections are assembled.

Heretofore in the construction of fireproof stairs it was necessary to cut, and drill the rivet holes in, the risers and treads for each particular job, and then rivet the same together at the job, but by the use of my invention this will become unnecessary and considerable time will thereby be saved.

In the accompanying drawings which illustrate my invention in its preferred form, and in which like reference numerals indicate corresponding parts throughout the several views—Figure 1 is a vertical longitudinal sectional view of a portion of a stairs constructed in accordance with my invention, and Fig. 2 is a transverse sectional view taken on the line 3—3 of Fig. 1, looking down.

Reference being had to the drawings and the reference numerals indicated thereon, 1 indicates a portion of one of the metal stringers of the stairs, to the inner side of which the risers and treads are attached.

The risers are indicated by the numeral 2, and each comprises a single piece of sheet metal, preferably sheet steel, the upper edge of which is bent forwardly, then upwardly, and then rearwardly, as at 3, 4, and 5, respectively, so as to form what is commonly termed a nosing. This nosing serves to prevent the edge of the plastic material A from chipping or breaking, and also to give the

stairs a neat and finished appearance. The lower edge of each of the risers is provided with a number of longitudinally arranged slots 6, for a purpose to be hereinafter referred to. The treads 7 are also formed of a single piece of sheet metal and each have their front edge bent upwardly at right angles, as at 8, the upper edge of which is flush with the upper side of the bent portion 3 of the riser 2. The rear edge of each of the treads is provided with a number of horizontally arranged slots 9 similar to the slots 6 of the risers 2. After the risers and treads have been cut to size and formed as above described, they are rigidly connected together by means of rivets 10 passing through the bent portions 8 of the treads and through the risers 2, and the sections kept in stock ready to be assembled in place on the stair stringers.

The means I employ for uniting the sections, comprises an angle bar 11, the horizontal flange of which is adapted to fit against the under side and adjacent the rear edge of the tread 7 of one section, and its vertical flange against the rear side, and adjacent the lower edge of the riser 2 of the next section above said tread. Both flanges of the angle bar 11 are provided with holes 12, in alinement with the slots 6 and 9 of the risers and treads respectively. Introduced through said holes and working in the slots 6 and 9 are bolts 13, the threaded ends of which receive clamping nuts 14. By this arrangement it will be seen that in assembling the sections the treads and risers may be readily adjusted according to the specifications, and by tightening the clamping nuts 14 they will be rigidly held at the desired adjustment. It will be noted that these clamping nuts 14 rest against the front faces of the risers 2 and the upper faces of the treads 7, so that when the concrete, or other plastic material A, is filled in, said nuts will be embedded therein and are consequently prevented from turning or becoming loose.

The variations in the dimensions of stairs are very slight, and by making the slots 6 and 9 of sufficient length risers and treads of one size may be used in practically all cases. The risers and treads may be secured to the stringers by means of the rivets 15 passing through tongues 16 formed on the ends of said risers and treads and bent at right angles thereto, and through the stringers. However, if desired, these tongues may

be omitted and the risers and treads secured to the stringers by means of the usual angle irons.

While I have shown and described my invention in its preferred form, it will be understood that various changes may be made without departing from the spirit thereof, and no limitation is implied by reason of the particular structure shown.

10 I claim:

1. A stair structure comprising a series of sections, each section embodying a riser and a tread, and means to adjustably connect the rear edge of the tread of one section to the lower edge of the riser of the next section thereabove.

2. A stair structure, comprising a series of sections, each section comprising a riser and a tread, slots formed in said risers adjacent their lower edges, and in said treads adjacent their rear edges, and means for adjust-

ably connecting the rear edge of the tread of one section to the lower edge of the riser of the next section above having elements to engage in said slots.

3. A stair structure, comprising a series of sections, each section comprising a riser and a tread, slots formed in said risers adjacent the lower edges, and in said treads adjacent their rear edges, angle bars connecting the tread of one section to the riser of the next section above, and bolts passing through the flanges of said angle bars and working in the aforesaid slots, and provided with clamping nuts, whereby the sections may be adjusted.

In testimony whereof I affix my signature in presence of two witnesses.

ALVAH A. GRINER.
